UNITED STATES PATENT OFFICE.

AMOS M. BARKER, OF BLOOMINGTON, NEBRASKA.

SINGLETREE-COUPING.

SPECIFICATION forming part of Letters Patent No. 653,542, dated July 10, 1900.

Application filed March 17, 1900. Serial No. 9,052. (No model.)

To all whom it may concern:

Be it known that I, AMOS M. BARKER, a citizen of the United States, and a resident of Bloomington, in the county of Franklin and 5 State of Nebraska, have invented a new and Improved Singletree-Coupling, of which the following is a full, clear, and exact description.

The purpose of the invention is to provide an improved means for attaching singletrees

- 10 to a doubletree, which means will permit a more extended range of movement of the singletrees than is at present attainable and the pivotal connection between the singletrees and doubletree rendered more durable, and
- 15 the singletrees may be capable of being raised and lowered relative to the doubletree, if desired.

The invention consists in the novel construction and combination of the several 20 parts, as will be hereinafter fully set forth, and pointed out in the claims.

Reference is to be had to the accompanying drawings, forming a part of this specification, in which similar characters of reference indicate 25 corresponding parts in all the figures.

Figure 1 is a plan view of a pole provided with the improved singletrees. Fig. 2 is a longitudinal section through the clevis or pivotal portion of a singletree, showing the pivotal 30 and locking device therefor in side elevation, the view being drawn on an enlarged scale and the doubletree appearing in section. Fig. 3 is a transverse section through the singletree, the doubletree, and the pivotal and locking device adapted for connecting the singletrees and doubletree, the view being on a 35 smaller scale than in Fig. 2; and Fig. 4 is a transverse section through the singletree, illustrating a clip or hook and a cockeye for the trace, through which the clip or hook is 40 passed, the cockeye being in section.

A represents a pole used in connection with a double team; B, a doubletree pivoted in any suitable or approved manner to the pole. C 45 represents singletrees having pivotal engagement with the doubletree, and D represents the neck-yoke, which is connected directly with the pole A in the customary manner.

A clip or hook 22 is located at each end of 50 each singletree C, and these clips or hooks are secured to the singletrees by bolts 23 or their equivalents. Each bolt and hook is provided

with two upwardly-extending prongs 24 and 25. The prongs 25 are the rear prongs and are longer than the forward prongs 24, and the rear prongs 25 are given an upward and rearward inclination to a decided extent, while the forward prongs 24 are curved slightly rearward and then upward and forward. The prongs 24 and 25 of the clips or 60 hooks are adapted to receive the cockeye 26 of the traces 27, and when the cockeyes are in place on the clips or hooks of the singletrees they are not liable to be accidentally displaced, but may be conveniently and expeditiously engaged with the clips or hooks or disengaged therefrom.

A particular form of coupling F is employed to connect the singletrees to the doubletree, and this improved form of coupling is illustrated in detail in Figs. 2 and 3, wherein it will be observed that a wear-plate 28 is secured upon the upper face of the doubletree at that point where the singletrees are to be pivotally connected with it. These wear-plates are provided with an inner annular flange and an outer annular flange, forming an annular sunken track 29, and each wear-plate 28 is also provided with a central opening. A mating wear-plate 30 is provided for each of the 80 lower wear-plates 28, and each upper or mating wear-plate 30 is provided with an annular flange 31, adapted to travel in the sunken track 29 of the lower wear-plate, and each upper wear-plate 30 is also provided with 85 a hub 32, which extends into the central opening of the lower wear-plate 28. Bolts 33 are passed through the doubletree and through the central portion of the pairs of wear-plates 28 and 30, turning loosely therein, and each 90 bolt is preferably provided with an enlarged upper portion 34, whereby shoulders 35 are formed on the bolts above the wear-plates and immediately above one leaf 36 of a hinge G, the other leaf 37 of the hinge being firmly 95 secured to one face of a singletree, which face is the front face of the said singletree when the said tree is in proper position on the doubletree. It will be understood that a hinge G is provided for each coupling F and for each 100 singletree C.

A link 38 is pivoted to an extension from the leaf 37 of each hinge attached to a singletree, and the said link is adapted to extend

over the head 34 of the bolt 33 of a coupling and to be engaged by the head 39 of a lever 40, one of said levers being hinged to the upper portion of each bolt 33, and the head 39 of each lever 40 is provided with an undercut recess adapted to receive the free end of the link 38, that the lever is intended to control. When the levers 40 extend downward, as shown in Figs. 2 and 3, the singletrees are carried to a position at such a distance above the doubletree that the singletrees will have perfect freedom of movement, and the singletrees are held in such position by the links 38, it being understood that the upper wear-plate 30 of each coupling which is connected with a singletree is free to turn on its mating lower wear-plate carried by the doubletree. When the levers 40 are carried upward, the links 38 may be disconnected from their heads and the singletrees may be dropped down to a position close to and in front of the doubletree, thus occupying but little space.

The hinge connection between the doubletree and the singletrees adds to the durability, strength, and economy of both, dispenses with all extra bolts, and enables the singletrees to turn freely on the doubletree, thereby allowing free play by the motion of the horses without strain of any part connected with the harness. In fact, the singletrees can be turned half-way around, enabling a passing vehicle to come very close to a vehicle thus equipped without danger of interference.

Having thus described my invention, I claim as new and desire to secure by Letters Patent—

1. A doubletree, singletrees pivoted on the doubletree, the singletrees having a hinged connection with the doubletree through their pivoted sections, links connected with said singletrees, and lock-levers engaging said links for locking the singletrees at an elevation above the doubletree.

2. A doubletree, interlocking wear-plates adapted to turn one upon the other, a pivot-pin passed through the said wear-plates, a hinge, a leaf of which is connected with the upper wear-plate, a singletree attached to the other leaf of the said hinge, and means for locking the singletree at an elevation above the doubletree, the lower wear-plate being secured to the doubletree.

3. The combination, with a doubletree, a wear-plate secured thereto, a pivot-pin passed

through the doubletree and through the said wear-plate, and a lock-lever carried by the upper end of said pivot-pin, of an upper wear-plate mounted to turn upon the lower wear-plate and around the pivot-pin, a hinge, a leaf of which is secured to the upper wear-plate, a singletree secured to the other leaf of the hinge, and a link connected with said singletree and arranged to pass rearwardly from the same to an engagement with said lock-lever, as set forth.

4. A doubletree, a singletree, a hinge having one leaf secured to the singletree, a pivot pin or bolt passed through the doubletree and through the other leaf of the hinge and projecting above the same, a locking-lever carried at the upper end of the pivot-pin, and a link carried by the singletree and adapted to be engaged by the lever to hold the singletree at an elevation above the doubletree.

5. The combination, with a doubletree, a singletree, a hinge having one leaf secured to the singletree and a pivot pin or bolt extending through the doubletree and through the other leaf of the hinge, the said leaf being arranged to turn on the doubletree, the said pivot pin or bolt having an enlarged upper portion forming shoulders above the said leaf of the hinge, of a link carried by the hinge-leaf secured to the singletree and adapted to extend over the upper end of the pivot-pin, and a lever pivoted to the upper portion of the pivot-pin and having a head provided with an undercut recess adapted to receive the free end of the link, substantially as described.

6. A singletree provided with hooks or clip, at its ends said hooks or clips each comprising a body portion secured to the singletrees and two spaced members which extend upward from the body at opposite sides of the end of the singletree, the rear member of each clip or hook being longer than the forward member and having an upward and rearward inclination, while the forward members of the clips or hooks are given a slight forward and upward inclination for the purpose described.

In testimony whereof I have signed my name to this specification in the presence of two subscribing witnesses.

AMOS M. BARKER.
